GUSTAV EGLOFF AND JACQUE C. MORRELL, OF CHICAGO, ILLINOIS, ASSIGNEES TO UNIVERSAL OIL PRODUCTS COMPANY, OF CHICAGO, ILLINOIS, A CORPORATION OF SOUTH DAKOTA.

PROCESS FOR THE CATALYTIC TREATMENT OF HYDROCARBON OIL.

Application filed May 10, 1922, Serial No. 559,719. Renewed September 5, 1928.

This invention relates to improvements in a process for treating hydrocarbon oils, and refers more particularly to the conversion of hydrocarbon oils under substantial pressure 5 in the presence of a catalytic agent.

Among the objects of the invention are to provide a process in which the oil is heated to a conversion temperature under substantial pressure, and is permitted to vaporize 10 in the presence of a catalyst whereby an improved quality distillate is obtained and a distillate containing less of unsaturate hydrocarbons.

The single figure is a diagrammatic side 15 elevational view of the apparatus. Referring to the drawings, the heating tubes 1 are mounted in furnace 2 which is preferably heated by means of gas burner 3. The heating tubes are connected by means of the 20 transfer line 4 controlled by the throttle valve 5 to a series of superimposed vapor chambers 6, 7 and 8, the lower chamber is connected to the transfer line by pipe 9 regulated by valve 10, the intermediate chamber 25 by a pipe 11 controlled by the valve 12, and the upper chamber by the line 13 regulated by the valve 14. The chambers are mounted in an insulated heating zone 15 to which the heated stack gases from the furnace may be 30 conveyed through the duct 16, or additional heat added by means of gas burner 17 mounted below the heating chamber. The stack 18 serves to carry off the spent gases of combustion.

35 Each chamber is equipped with a vapor draw-off line 19 controlled by valves 20 which lead to a common pipe 21 which has connection with the dephlegmator 22 through an intermediate connection 23 controlled by valve 24. The dephlegmator is connected to water condenser coil 25 mounted in the condenser box 26 by pipe 27 regulated by valve 28. The condenser coil in turn is connected by line 29 to receiving tank 30 which is 40 equipped with pressure relief valve 31, liquid draw-off valve 32, pressure gauge 33 and a liquid level gauge 34.

The reflux liquid condensed in the dephlegmator is returned through the line 35 45 regulated by valve 36, and may be either drawn off through the line 37 in which is in-

terposed the valve 38, or may be returned through the line 39 by proper manipulation of the valves 36, 38 and 44. Reflux oil and catalytic material returned through the lines 35 and 39 may be charged by the pump 41 back to the heating tubes. The prolongation 21^a of the pipe 21 connected with the lines 19 serves as a draw-off pipe for any condensed catalytic material which is separated 55 out in these lines. This liquid may be drawn off from the system through pipe 42 controlled by valve 43 or recharged directly with the reflux condensate from the dephlegmator to the heating tubes by closing the valve 43 60 and opening the valve 44.

In operation the oil to be treated is introduced from any convenient source through the line 45 and is charged by means of the pump 46 through the inlet line 47 to the heating tubes 1 which preferably consist of a continuous coil mounted in the furnace. The oil in its travel through the heating zone is raised to a cracking temperature while a substantial pressure of the generated vapors is maintained during treatment.

The oil while at conversion temperature passes through the transfer line and may be directed to any one or all of the vapor chambers 6, 7 or 8 through their separate secondary connections. In the bottom of each vaporizing chamber is maintained a quantity of aluminum turnings or any type of disintegrated aluminum in a relatively comminuted state. During treatment there is introduced through the transfer line and through the body of the heated oil regulated quantities of hydrogen chloride or chlorine through the pipe 48 controlled by the valve 49. This gaseous re-agent in combination with the aluminum material in the vapor chambers produces a catalytic substance which promotes materially the conversion of the oil and the quality of the distillate produced therefrom. The vapors evolved in the vaporizing chambers pass off through the draw-off lines 19 to the dephlegmator through the connecting pipes 21 and 23 where the vapors are subjected to a refluxing action. There is carried with these evolved vapors portions of the catalyst 55 in a sublimed state. Some of the catalyst is separated out with the reflux condensate in 60

the dephlegmator zone and other portions are relieved from the oil vapors in the lines 19 and 21. The separated catalyst relieved from the vapors in lines 19 and 21 may be drawn off from the system through the pipe 42 as explained, or may be returned and re-cycled with the reflux condensate to the heating zone for re-treatment. The still vaporized portion of the hydrocarbon vapors rise to the top 10 of the dephlegmator and pass over to the water condenser, thence to the receiver where they are collected as distillate. Any catalytic substance which may remain with the vapors is drawn off from the receiver after gravity 15 separation. The catalytic treatment of the oil may take place under substantial pressure or under differential pressures maintained in the respective zones by the valves interposed there between. By the alternate use of the 20 different vaporizing chambers, one or more may be cut out for cleaning and recharging with the aluminum turnings. In place of the hydrogen chloride, a mixture of regulated quantities of hydrocarbon vapors and chlorine 25 may be introduced through line 48 and simultaneously passed through the separate inlet pipes 19 if all the chambers are employed. Thus the most advantageous conditions may be produced in the conversion 30 in the vaporizing chambers by regulating the quantities of the different gases injected.

In practice, mid-continent gas oil of from 30 to 32° Baumé being treated to temperatures ranging from 700 to 900° F., and pressures from 50 to 200 pounds have yielded 25 to 35% of high quality distillate with relatively low percentage of unsaturated hydrocarbons,

the distillate ranging in gravity from 48 to 52° Bé.

We claim as our invention:

1. A process for the conversion of hydrocarbon oil, consisting in initially raising the oil to a cracking temperature, in injecting into the oil, while at a cracking temperature, regulated quantities of hydrogen chloride, in passing the commingled heated oil and hydrogen chloride into an enlarged zone containing a quantity of disintegrated aluminum, in taking off vapors from said enlarged zone for condensation and collection, and in maintaining a superatmospheric vapor pressure on the oil undergoing conversion in the process.

2. A continuous process for the conversion of hydrocarbon oil, consisting in raising the oil to a cracking temperature in a heating zone, in introducing into the oil, while at a cracking temperature, regulated quantities of hydrogen chloride, in passing the heated hydrocarbon oil and the contained hydrogen chloride into an enlarged vapor chamber, wherein a substantial quantity of disintegrated aluminum is maintained, in taking off vapors evolved from the oil from said vapor chamber, in subjecting such vapors to partial condensation, in returning the condensate separated from the vapors to said heating zone for further treatment, in subjecting the vapors uncondensed by subjection to said partial condensation to final condensation, in collecting the resulting distillate, and in maintaining a superatmospheric pressure on the oil undergoing conversion in the process.
